DESIGN FOR A PRISMATIC PENDANT

Irving Levin, New York, N. Y., assignor to Elite Glass Co. Inc., New York, N. Y., a corporation of New York

Application September 7, 1939, Serial No. 87,077

Term of patent 3½ years

To all whom it may concern:

Be it known that I, Irving Levin, a citizen of the United States, residing in the city of New York, in the county of New York and State of New York, have invented a new, original, and ornamental Design for a Prismatic Pendant, of which the following is a specification, reference being had to the accompanying drawing, forming part thereof.

Fig. 1 is a front elevational view of a prismatic pendant showing my new design; and
Fig. 2 is a side view thereof.

I claim:

The ornamental design for a prismatic pendant, substantially as shown.

IRVING LEVIN.
